UNITED STATES PATENT OFFICE.

EDWARD J. MILLER, OF CAMBRIDGE SPRINGS, PENNSYLVANIA

BOTTLE.

No. 826,261.

Specification of Letters Patent.

Patented July 17, 1906.

Application filed May 3, 1906. Serial No. 314,969.

To all whom it may concern:

Be it known that I, EDWARD J. MILLER, a citizen of the United States of America, residing at Cambridge Springs, in the county of Crawford and State of Pennsylvania, have invented certain new and useful Improvements in Bottles, of which the following is a specification, reference being had therein to the accompanying drawings.

10 This invention relates to certain new and useful improvements in bottles; and the invention relates more particularly to bottles that cannot be refilled and disposed of as the original article.

15 It is a well-known fact that certain parties refill bottles that once contained popular brands of liquids with an inferior article and represent and dispose of the same as the original article.

20 The primary object of this invention is to dispense with this nefarious practice by devising a bottle which cannot be refilled surreptitiously and fraudulently sold as the original article, the bottle being of such a construction as to be disfigured when it is first opened.

25 The preferred embodiments of my invention, which will be hereinafter more fully described and then specifically pointed out in the claims, are illustrated in the accompanying drawings, wherein—

30 Figure 1 is a vertical sectional view of a portion of the bottle constructed in accordance with my invention. Fig. 2 is a perspective view of the closure-lock. Fig. 3 is a vertical sectional view of a closure-locking sleeve or auxiliary neck portion used in connection with the bottle. Fig. 4 is a horizontal sectional view taken on the line $z-z$ of Fig. 3.

35 In putting my invention into practice I use a conventional form of bottle 1, having a contracted neck portion 2, adapted to receive a stopper or cork 3. Upon the breast 4 of the bottle and surrounding the contracted neck portion 2 is secured a closure-locking sleeve 5, the sleeve being constructed of a material similar to the bottle 1, glass or similar vitreous material being employed for this purpose. The sleeve or auxiliary neck 40 portion 5 has its lower edges beveled, as at 6, to conform to the breast 4 of the bottle 1, and these beveled edges of the sleeve are fused or otherwise secured and made a part of the bottle, as at 7. The upper end of the sleeve 45 or auxiliary neck 5 extends a slight distance above the neck portion 2 of the bottle, and

the inner walls of the sleeve are provided with two diametrically - opposed vertical grooves 8 8, the lower ends of said grooves terminating in recesses 9 9, formed in the lower inner edges of the sleeve 5.

In combination with the sleeve or auxiliary neck 5 I employ a locking-closure 10, said closure comprising a cap 11, having depending diametrically-opposed arms 12 12, the lower ends of said arms being bent upwardly at an inclination, as at 14 14. The arms 12 12 are preferably constructed of a material having resilient or yielding properties, the object of which will be presently described. 70

In practice bottles will be equipped with the sleeves or auxiliary necks 5 at the factory where they are manufactured, and accompanying each bottle will be a locking-closure which can be readily placed within the sleeve 75 or auxiliary neck 5 to retain a cork or stopper within the neck portion 2 of the bottle 1. The operation of locking the stopper or cork within the neck of the bottle 1 is extremely simple and can be quickly performed, it only 80 being necessary to place the bent ends of the arms 12 12 of the locking-closure 10 in the grooves 8 8 and force the locking-closure downwardly until the contracted ends 14 14 of the locking-closure expand within the recesses 9 9 of the sleeve or auxiliary neck 5, at which time it will be impossible to remove the stopper or cork 3 unless the sleeve or auxiliary neck 5 is severed from the bottle 1 or the cap 11 cut or punctured to permit of easy 90 access being had to the stopper or cork 3. The device which I have just described for closing the neck portion of a bottle is also applicable to the necks of jugs, demijohns, carboys, flasks, and such receptacles or articles 95 that might be repeatedly used and in some instances fraudulently used.

It is thought that the construction, arrangement, and operation of the various parts of my improved bottle will be readily 100 understood from the foregoing description, taken in connection with the drawings, it being obvious that such changes in the size, proportion, and minor details of construction as are permissible by the appended claims may 105 be resorted to without departing from the spirit and scope of the invention.

What I claim, and desire to secure by Letters Patent, is—

1. The combination with a bottle having a neck portion, of a locking-closure sleeve secured to the breast of said bottle, and sur-

rounding said neck portion, said sleeve having grooves formed therein terminating in recesses formed at the lower inner edges of said sleeve, a locking-closure adapted to fit 5 within said grooves and closing the neck portion of said bottle, and means engaging in said recesses to lock said closure within said sleeve, substantially as described.

2. The combination with a bottle having 10 an opening, of a sleeve secured to the breast of said bottle, said sleeve having vertically-disposed grooves formed therein, and means engaging in said grooves to close the opening of said bottle, substantially as described.

3. The combination with a bottle, of a 15 closure comprising a cap fitting over the mouth of the bottle-neck, arms depending from said cap and having their ends turned upward, and a sleeve inclosing the bottle-neck and formed with recesses to receive said 20 arms.

In testimony whereof I affix my signature in the presence of two witnesses.

EDWARD J. MILLER.
